UNITED STATES PATENT OFFICE.

JACOB BLOSSER, OF CALIFORNIA, MISSOURI.

NUT-LOCK.

SPECIFICATION forming part of Letters Patent No. 242,744, dated June 14, 1881.

Application filed August 2, 1879.

To all whom it may concern:

Be it known that I, JACOB BLOSSER, of California, in the county of Moniteau, and the State of Missouri, have invented certain new and useful Improvements in Nut-Locks, of which the following is a specification, reference being had to the annexed drawing, which is a longitudinal sectional view.

In said drawing, A represents the rail, B the bolt, and A' A² the fish-plates, of a rail-joint to which my invention has been applied.

My invention consists in forming in the outer fish-plate, A², recesses to receive flexible washers D, adjoining which other flexible washers 15 D' D² are placed upon the common bolt B to be tightened and compressed by a nut, C, having a recess, C', encompassing the outer wash-

er, D². The central flexible ring, D', is surrounded by a metallic washer, E, to prevent undue expansion, by which the rings D and 20 D² might be forced out of their sockets.

Having thus described my invention, I claim and desire to secure by Letters Patent of the United States—

As an improvement in nut-locks, the combination of the recessed plate A², elastic washers D D' D², recessed nut C, and the ring or washer E, substantially as herein described, for the purpose shown and specified. 25

JACOB BLOSSER.
